UNITED STATES PATENT OFFICE.

WILLIAM MAGUIRE AND ALBERT BAUSCH, OF BROOKLYN, NEW YORK.

SNAP FOR BRACELETS.

1,353,772.

Specification of Letters Patent. Patented Sept. 21, 1920.

Application filed March 29, 1920. Serial No. 369,500.

To all whom it may concern:

Be it known that we, WILLIAM MAGUIRE and ALBERT BAUSCH, both citizens of the United States, and residents of the city of 5 New York, borough of Brooklyn, in the county of Kings and State of New York, have invented a new and useful Snap for Bracelets, of which the following is a full, clear, and exact description.

10 This invention relates to snap fasteners or catches for bracelets, and has for an object the provision of an improved construction which is easily operated and which when snapped closed will positively remain 15 closed under any and all conditions except the usual opening action.

Another object of the invention is to provide a snap fastener for flexible bracelets in which interlocking hooks are provided 20 having overhanging members whereby the hooks must pass each other and then come back to a locked position, thus assuring a positive interlocking action.

A further object of the invention is to 25 provide a snap fastener for bracelets wherein one end of the bracelet is provided with a pair of rigid hooks facing each other and the other end is provided with a pair of resilient hooks adapted to snap into the 30 rigid hooks within the boxing of part of the bracelet.

In the accompanying drawing:

Figure 1 is a top plan view of a snap fastener embodying the invention, the same 35 being shown with the complete bracelet in dotted lines.

Fig. 2 is a top plan view of the snap fastener shown in Fig. 1 with certain parts 40 broken away for better illustrating the hooks embodying certain features of the invention.

Fig. 3 is a fragmentary sectional view through Fig. 1 on line 3—3.

Fig. 4 is a transverse sectional view 45 through Fig. 1 on line 4—4.

Fig. 5 is a longitudinal sectional view through Fig. 2 on line 5—5.

Fig. 6 is a side view of the spring hooks shown in Fig. 2.

50 Referring to the accompanying drawing by numerals, 1 indicates a bracelet of any desired kind which is provided with a snap fastener 2 of special construction. The snap fastener 2 is provided with what is known as a double box 3, in which is soldered or otherwise secured a plate 4 having

integral hooks 5 and 6, said hooks having overhanging shoulders 7 and 8 in the nature of ordinary fish hooks, so as to coact with the overhanging shoulders 9 and 10 of the 60 spring catch 11. It will be noted that the plate 4 extends from the box 3 into a double box 12, and in the box 12 interlocks with a spring catch 11. This spring catch is provided with hooks 13 and 14 carrying the 65 overhanging shoulders 9 and 10 and a spring loop 15 surrounding the upstanding tubular post 16 preferably formed integral with box 12 as shown in Fig. 4.

The box 12 is provided with suitable apertures on both sides through which the pins 17 and 18 extend, said pins having enlargements or heads 19 and 20, which also may be roughened as they are engaged by the fingers in pressing the spring catch 11 for 75 disengaging the hooks 13 and 14 from hooks 5 and 6.

The snap fastener 2 may be connected with the flexible bracelet 1 formed with a number of boxes designed to receive diamonds or other stones, similar to the boxes indicated by the numeral 3, or may be connected with solid bracelets hinged together at one point. By providing the overhanging and interlocking shoulders 7 and 8 and 80 also the shoulders 9 and 10 the parts are so interlocked as to positively resist disengagement, the spring 15 continually urging the hooks 13 and 14 outwardly. When it is desired to disengage the catch the thumb 90 and finger is pressed against the enlargements 19 and 20 whereupon the hooks 13 and 14 are pressed together and away from the hooks 5 and 6, so that the hooks 5 and 6, plate 4 and associate parts may be moved 95 away from the spring catch 11 and thus cause the bracelet to be opened. To close the bracelet it is merely necessary to place the hooks 5 and 6 into the end of the box 12 and then force the parts together until 100 a snap is heard, which will cause the parts to assume the position shown in Fig. 2, said position being a completely locked position.

What we claim is:

1. A catch for flexible bracelets comprising a plate adapted to be connected with one end of the bracelet and projecting therefrom, said plate having a pair of facing integral hooks, each hook being formed with an overhanging shoulder, a coiled member 110 having ends formed as hooks with overhanging shoulders, the coil proportioned to

act as a spring, said coiled member being arranged wholly within part of the opposite end of said bracelet to said plate and positioned to snap into interlocked relationship with said first mentioned hooks when the part of said plate including the hooks are inserted in the end of the bracelet carrying the coiled member, and manually actuated means for disengaging the hooks of the coiled member from the first mentioned hooks.

2. A catch for flexible bracelets comprising a plate adapted to be connected with one end of a bracelet and projecting there-

from, said plate having a pair of hooks, a 15 pair of resilient hooks carried by the opposite end of said bracelet and positioned wholly within part of the opposite end of said bracelet to said plate and arranged to snap into interlocked relationship with the 20 first mentioned hooks when the parts of said plate including said hooks are inserted in the end of the bracelet carrying the second mentioned hooks, and manually actuated means for disengaging the second men- 25 tioned hooks from the first mentioned hooks.

WILLIAM MAGUIRE.

ALBERT BAUSCH.
